UNITED STATES PATENT OFFICE.

SAM CHRISTENSON AND ARTHUR E. CHRISTENSON, OF FERGUS FALLS, MINNESOTA.

ILLUMINATED SIGN.

Application filed February 16, 1923. Serial No. 619,529.

To all whom it may concern:

Be it known that we, SAM CHRISTENSON and ARTHUR E. CHRISTENSON, citizens of the United States of America, residing at 5 Fergus Falls, in the county of Otter Tail and State of Minnesota, have invented certain new and useful Improvements in Illuminated Signs; and we do hereby declare that the following is a full, clear, concise, and 10 exact description of the invention, such as will enable others skilled in the art to which it appertains to make and use the same.

This invention relates to improvements in illuminated signs, having for an object to 15 provide a sign especially advantageous for use along highways during darkness, whereby to signal to an observer in an approaching motor driven vehicle, information or knowledge concerning the condition or 20 course of the preceding portion of such highway, the sign being operable by the reflection and re-reflection of the light rays emitted from the headlights of the approaching vehicle, whereby to cause the display of 25 certain words upon the front portion of the same in a manner which will attract the attention of the operator thereto and likewise, be easily read or understood by him.

We are aware that various devices have 30 heretofore been employed with varying degrees of success, wherein it is the purpose to signal certain information to the operators of vehicles travelling a highway so equipped, during darkness. Amongst these devices are different forms of constantly illuminated signs, both of the lamp box and light flooded type. Because of the glare and reflections from such devices as well as the cost 35 of maintenance thereof, however, they have 40 been found to be exceedingly objectionable and even impracticable. With our improved device, there will be no confusing or disconcerting glare in the eyes of the operator of an approaching vehicle and it will not be 45 until the light rays from the headlights of the vehicle strike the same that it will be illuminated in a manner to effectually signal to the vehicle operator. Furthermore, because of the fact that the sign depends for 50 its illumination upon the headlights of a vehicle, it will be appreciated that the cost of maintenance thereof will be practically nil.

In order that the invention and its mode 55 of operation may be readily understood by

persons skilled in the art, we have in the accompanying illustrative drawings, and in the detailed following description based thereon, set out one possible embodiment of the same.

60 In these drawings:

Figure 1 is a perspective view of the improved signal having a portion of its top and end wall broken away and shown in section; and,

65 Figure 2 is a vertical transverse section through the improved signal showing the course of the reflected and re-reflected light rays emitted from the headlights of an approaching motor driven vehicle.

70 Having more particular reference to the drawings, the improved device may be stated to comprise a substantially rectangular shaped housing generally indicated by the numeral 1, including top, bottom, and rear 75 walls, while the front wall thereof is open and is adapted to receive therein a transparent plate 2, the marginal portions of which are suitably engaged in the adjacent portions of the top and bottom and end walls 80 as indicated by the numeral 3, whereby to prevent displacement of the same.

Positioned within the housing 1 at an angle of approximately forty-five degrees is a reflector or mirror 4, having its opposite 85 marginal portions immovably engaged with adjacent portions of the bottom and rear walls of the housing, as shown in Figure 2.

Supported in the upper portion of the housing 1 adjacent the top wall thereof and in parallelism to the same is a rack 5 having a plurality of inwardly opening superposed grooves therein.

90 Engaged in the lowermost of the grooves in the rack 5 is a stencil plate 6 having certain matter cut therefrom in the usual manner. Disposed directly above the stencil plate 6 and in parallelism thereto, being supported in the intermediate groove of the rack 5, is a translucent colored plate 7, while 95 directly above this plate 7, there is arranged a second reflector 8, said reflector being engaged in the uppermost grooves of the rack 5 and positioned in parallelism to the top 100 of the housing 1 and the translucent colored plate 7.

105 In use of the improved signal, the same is supported upon a suitable bracket, standard, et cetera, at a point in proximity to one side of a highway, the open front wall there- 110

2

of being disposed so as to face approaching vehicular traffic upon that particular side of the highway. With the approach of a motor driven vehicle in darkness, the light rays emitted from the headlights thereof will be directed onto the angularly positioned reflector 4, in the manner indicated by the dotted dash lines in Figure 2, from whence they will be reflected directly up-
 10 wardly as also indicated by the dotted dash lines, passing through the stencilled portion of the plate 6, and through the translucent colored plate 7 for re-reflection upon the second reflector 8 positioned in proximity
 15 to the top of the housing 1. The reflected light rays contacting with this second reflector will be immediately re-reflected and caused to retract their initial course, thus effecting the projection of a colored letter
 20 or word corresponding to the stencilling of the plate 6 upon the transparent plate 2 arranged adjacent the open front wall of the housing 1. By reason of the coloring of the letter or word or other matter presented
 25 upon the transparent plate 2, it will be appreciated that the same will serve to immediately attract the attention of the vehicle operator thereto. Likewise, because of the mode of presentation of the reflected mat-
 30 ter upon the transparent plate 2, the same may be readily read or understood by an observer.

Manifestly, the construction shown is capable of considerable modification and such modification as is within the scope of our claims, we consider within the spirit of our invention.

We claim:

1. A sign comprising a housing having an open front wall, a transparent plate in said open front wall, an angularly positioned reflector within said housing, a second reflector positioned adjacent the top of the housing parallel thereto, and a stencil plate arranged immediately below said second reflector in parallelism thereto. 40
2. A sign comprising a housing having an open front wall, a transparent plate in said open front wall, an angularly positioned reflector within said housing, a translucent colored plate directly below said reflector and a stencil plate arranged immediately below said translucent colored plate and in parallelism thereto. 45
3. A sign comprising a housing having an open front wall, a transparent plate in said open front wall, a reflector positioned within the housing at an angle of approximately forty five degrees, a grooved rack supported in the upper portion of said housing in parallelism to its top, a second reflector supported in the upper portion of said rack in parallelism to the top of the housing, a stencil plate supported in the lower portion of said grooved rack and in parallelism to the second reflector, and a translucent colored plate supported by the rack intermediate of said stencil plate and second reflector. 55

In witness whereof we have hereunto set 70
 our hands.

SAM CHRISTENSON.
 ARTHUR E. CHRISTENSON.
